UNITED STATES PATENT OFFICE.

PTOLLMAN STOVER AND LUDLOW CHAMBERS, OF VISALIA, CALIFORNIA.

SEAL-LOCK.

No. 927,294.

Specification of Letters Patent.

Patented July 6, 1909.

Application filed September 1, 1908. Serial No. 451,219.

To all whom it may concern:

Be it known that we, PTOLLMAN STOVER and LUDLOW CHAMBERS, citizens of the United States, residing at Visalia, in the 5 county of Tulare and State of California, have invented new and useful Improvements in Seal-Locks, of which the following is a specification.

The invention relates to an improvement 10 in seal locks, being particularly directed to a construction whereby a car seal may be sealed against unauthorized opening without so destroying the seal as to provide the knowledge of such opening.

15 The main object of the present invention is the provision of a seal lock which is readily adapted for use with a car of any construction and which is not designed to form a permanent part of the car structure, the construction providing for securing a sealing strip in place against unauthorized removal without notice.

20 The invention will be described in the following specification, reference being had particularly to the accompanying drawings, in which:—

25 Figure 1 is a view in elevation illustrating the construction and application of our improved seal lock. Fig. 2 is a longitudinal 30 section, partly in elevation, taken through the lock. Fig. 3 is a transverse broken sectional view taken through the lock. Fig. 4 is an elevation of the sealing strip.

35 Referring particularly to the accompanying drawings, our improved seal lock comprises a lock 1, which is approximately rectangular in shape and formed with a recess 2 of the form shown in Fig. 2. Within the recess is mounted the locking dog 3 comprising 40 a spring member having one terminal forced into the material of the lock, as at 4, and projected rearwardly from said point of attachment within the recess and terminating in a latch nose 5 formed by inclining the material 45 of the dog outwardly and then inwardly at right angles to form a squared edge 6 from which the material extends rearwardly, as at 7, and then inwardly to provide a stop 8, all as clearly shown in Fig. 2. The lock is completed and the recess 2 closed by a cover 50 plate 9 in the inner surface of which is formed a recess 10 to receive the relatively outer edge of the latching portion of the locking dog when the latter is in normal position under the influence of its inherent resiliency, as previously noted. The relatively upper sur-

face of the block forming the lock 1 is formed with a longitudinal recess 11 extending throughout the length of the block and overlying the recess 2, said recesses 11 and 2 being, of course, in communication and the latter being of materially less width than the former. The recess 11 is practically coextensive in depth with the thickness of the sealing strip to be hereinafter referred to, and it will be noted from Figs. 2 and 3 of the drawings that the locking dog, when in operative position, has the latching nose thereof projected across the recess 11 and within the channel 10 in the cover plate. 60 65 70

The lock and cover plate are secured together by a band 12 arranged to encircle the parts and having the sections of said band extended upwardly in contact to form a supporting arm 13. The upper end of the arm 75 loosely engages a ring 14, which is preferably secured to a chain 15 depending from an eye bolt 16 secured to the car door. The sealing strip comprises an elongated strip 17 constructed of material usual in forming such 80 strips. The strip is of such sectional dimensions as to be adapted for free movement within the recess 11 in the lock, being provided at one end with a disk head 18 of a width exceeding that of the strip and being 85 formed adjacent the opposite end with an opening 19, which is of a size to receive the nose end of the locking dog. Suspended from the ring 14 is a guide member 20 formed at the lower end with a loop 21 to permit the 90 passage therethrough of the strip, said guide member being of such length that in normal position the loop 21 thereof will align with the recess 11 in the lock.

In use the sealing device is suspended from the eye bolt 16 so that the lock 1 alines with an eye bolt 22 secured to the car adjacent the edge of the door opening. With the car door closed ready for sealing, the end of the sealing strip opposing the disk head 18 is passed 95 through the eye bolt 22, the loop 21 of the guide arm, and into the recess 11 of the lock, said strip being moved rearwardly and serving to depress the nose end of the locking dog until the opening 19 of the strip registers 100 with said nose end. In this position the inherent resiliency of the locking dog will force the nose end thereof through the opening 19, thereby locking the strip against withdrawal 105 in a direction opposite to that by which it was inserted. As the disk head 18 is of materially greater transverse dimensions than the 110

remainder of the strip 17, it is obvious that said head cannot be passed through any of the parts through which the strip was inserted in the sealing operation. Therefore, 5 the locking dog prevents movement of the strip in one direction while the disk head prevents movement thereof in the opposing direction. The disk head is of a size to readily receive any desired impression by the 10 officials, and the material of the strip is preferably such as to permit the impression in the usual manner.

It is to be particularly noted that the locking edge 6 of the nose 5 inclines forwardly and 15 downwardly relative to the direction of pull on the sealing strip 17, whereby the rear edge of the opening 19 in said strip will, in the forward pull on said strip tend to force the nose 5 of the locking dog upwardly and into the 20 recess 10 in the cover. By this construction the stronger the pull on the sealing strip the tighter the latch nose is held in locking position.

When desired to unseal the car the disk 25 head is severed from the body of the strip by any ordinary cutting implement, whereupon the strip may be freely withdrawn from the locking member in a direction similar to that by which it was initially inserted.

30 It is at once apparent that the improved structure is readily adapted for use with any type of car and that it may be readily removed from one car and applied to another if desired. Furthermore, the application of 35 the seal is a simple and speedy operation, requiring no particular care or skill, and also when the seal is in place it is impossible

to open the car without destroying the seal and thereby giving notice of such attempt.

Having thus described the invention what 40 is claimed as new, is:—

A seal lock including a body formed in one surface with a longitudinal channel and with a recess communicating with the channel, a locking dog comprising a length of spring 45 material terminally secured in the body at one end of the recess and having a locking shoulder inclined forwardly and downwardly toward the forward edge of the body, said shoulder operating in the recess in the body, 50 a cover plate formed with a recess to register with the recess in the body and receive the shoulder of the locking dog when the latter is in operative position, means for suspending the lock, and a seal strip freely slidable in the 55 channel in the body in one direction, said strip being formed with an opening to permit the passage of the shouldered end of the dog therethrough, the rear edge of the opening bearing against the inclined portion of the 60 locking shoulder, whereby forward pull upon the strip when in operative position will force the locking shoulder into the recess in the cover.

In testimony whereof we affix our signatures in presence of witnesses.
